HOLDER FOR ARTIFICIAL FLORAL PETALS AND LEAVES

Leon Jack Mitchell, 29 Wadeson St.,
London E.2, England

Filed Dec. 27, 1972, Ser. No. 318,742

Claims priority, application Great Britain June 29, 1972

Term of patent 14 years

Int. Cl. D11—02

U.S. Cl. D29—1 R

FIG. 1 is a side elevation of the holder for artificial floral petals and leaves showing my new design;

FIG. 2 is a top plan view;

FIG. 3 is a sectional view taken on line 3—3 of FIG. 1; and

FIG. 4 is an exploded side elevational view.

I claim:

The ornamental design for a holder for artificial floral petals and leaves, substantially as shown and described.
